UNITED STATES PATENT OFFICE.

GEORGE A. LONG, OF BOSTON, MASSACHUSETTS.

SALVAGING APPARATUS.

1,324,425.

Specification of Letters Patent.

Patented Dec. 9, 1919.

Application filed July 2, 1917. Serial No. 178,162.

To all whom it may concern:

Be it known that I, GEORGE A. LONG, a citizen of the United States, residing at Boston, in the county of Suffolk and State of 5 Massachusetts, have invented new and useful Improvements in Salvaging Apparatus, of which the following is a specification.

My invention relates to a submarine salvaging apparatus and its object is to provide 10 an apparatus of this kind, by means of which, one or more operators may descend to a submerged vessel, inspect same, and positively attach cables and the like thereto, in 15 any desired number, by means of which the vessel may be raised to the surface by suitable hoisting and flotation means. This apparatus is particularly adapted to descend to comparatively great depths and yet enable 20 the operators therein to perform their work and to coöperate and communicate with attendants at the surface.

Figure 1 is a sectional side elevation of the apparatus on line 1—1 of Fig. 2;

25 Fig. 2 is a plan;

Fig. 3 is a partial end elevation;

Fig. 4 is a sectional elevation of a fixture for drilling through the steel sides of a vessel;

30 Fig. 4^a is an enlarged view of a portion of fixture shown in Fig. 4;

Fig. 5 is a section on 5—5 Fig. 4;

Fig. 6 is a sectional elevation of a fixture for boring through the sides of a wooden 35 vessel;

Fig. 7 is a sectional elevation of the bow end of apparatus on 7—7 of Fig. 9;

Fig. 8 is a sectional plan of the bow end of the apparatus;

40 Fig. 9 is a sectional elevation on 9—9 of Fig. 7 looking forward;

Fig. 10 is an enlarged sectional elevation of a fixture for grappling a vessel through a port hole or other opening;

45 Fig. 11 is an end elevation of the above fixture;

Fig. 12 is an enlarged section on line 12—12 of Fig. 1 looking aft;

Fig. 13 is a portion of a sectional side elevation amidships on line 13—13 of Fig. 12;

50 Fig. 14 is a sectional side elevation of the stern portion of this apparatus on line 14—14 of Fig. 15;

Fig. 15 is a sectional end elevation on line 55 15—15 of Fig. 14 looking aft; and

Fig. 16 shows the method of grappling a sunken vessel through the portholes.

Referring to the drawings, the operating mechanism is inclosed in a shell comprising a cylindrical body 20 and the heads 21 and 22 joined thereto.

Suitable openings are provided for purposes hereinafter described, the heads and all such openings being so joined and protected against leakage as to form a watertight compartment, within which the operators may conveniently move in order to observe and to control the action of the apparatus. The shell 20 is reinforced against collapsing by suitable bands 23, and ribs 24 on heads 21, 22, the whole forming a structure capable of withstanding a heavy pressure of surrounding water.

In the top of the structure and forming an integral part thereof is the manhole 25, closed by the cover 26, which is connected thereto by a hinge joint 27 or other suitable method. A packing ring 28 interposed between the flanged top of the manhole and the under surface of the cover insures a watertight joint, and a locking arm 29 is provided, whereby the cover may be clamped in place by the operators within. For emergency use the locking arm is secured to shaft 30 extending through the cover and provided with the handle 31 by means of which the cover may be unlocked from the outside; a packing box and gland insuring watertight conditions where the shaft passes through the cover. Surrounding the manhole is the platform 33 supported by brackets 34 secured to the shell, a hand rail 35 being provided as a protection for the operators, in entering or leaving the manhole.

Within the shell, the fittings and attachments necessary to the operation of the apparatus, are disposed with due regard to convenience, economy of room and balance of weight.

In the preferred form shown, storage batteries 36 are disposed on either side of the longitudinal axis, and connected to form one unit. Supported from the top of the shell are tanks 37 for compressed air also connected to form one unit. Water tanks 38 are fitted to the bottom, and for convenience are made in sections, several such sections being united by water tight joints 39 to form an independent unit, two such units being shown in the accompanying drawings. To 100 105 110

resist the pressure of the water, each section is reinforced by suitable ribs or stays 40.

In the preferred form of apparatus here-
5 in shown and described, it is proposed to employ two operators, cooperating with each other but having independent duties, and for purposes of distinction, they may be designated as operator and assistant respec-
10 tively. It is obvious, however, that the apparatus may be operated by one man by rearranging the controlling mechanism. Broadly speaking the duties of the operator are those that pertain to the guidance and
15 control of the apparatus in grappling a sunken vessel, and the duty of the assistant consists in controlling, under orders, the water, air and vacuum tanks, and in giving such auxiliary help as may be required by
20 the operator.

Mounted over the rear water tank is the motor 41, the center line of its shaft 42 being coincident with the center line of the propeller shaft 43, mounted in the extension 44 of the head 22. To prevent leakage where the shaft passes through the shell to the propeller 45 there is provided a packing 46 and gland 47, and housed in the extension 44 is indicated the thrust-bearing 48 of any
25 suitable construction, against which the propeller and propeller shaft react.

Connection between the motor shaft and the propeller shaft is made by means of the clutch member 49 mounted on the motor
35 shaft and slidably thereon, and the clutch member 50 rigidly mounted on the propeller shaft, the member 49 being operated to engage the member 50 by means of the forked connection 51 engaging the groove 52 in
30 clutch member 49.

The forked connection is mounted on the shaft 53 journaled in the bearings 54, and is rigidly connected to one end of the lever 55.

To the other end of the lever is pivoted the
45 connection 56 which is extended forward and pivotally joined at its other end to the hand lever 57.

This lever is pivotally mounted in the bracket 58 and is provided near its upper
50 end with a spring latch 59 which engages the arc 60, supported on standards 61, secured to the water tank 38 in such position that the lever may be operated by the pilot.

Extending fore and aft in a convenient
55 location is the shaft 62 journaled in suitable bearings as at 63. Rigidly secured near the rear end of the shaft is the pulley 64 alined with the corresponding pulley 65 mounted on the motor shaft 42, and driven therefrom
60 through the medium of the belt 66. Near the forward end of the shaft 63 is the clutch pulley 67 loosely mounted thereon, and which may be engaged by the clutch member 68 slidably mounted on shaft 62 and operates by means of the lever 69 pivoted at 70,

and engaging the groove 71 in clutch member 68. Lever 69 is so placed that it may be readily operated by the pilot.

Journalized in the inwardly extending hub 72 of the forward head 21 is a shaft 73 the forward end of which is enlarged at 74 and provided with a socket 75 shaped to engage corresponding projections 76 formed on the ends of the several fixtures, to be hereafter described, that may be used in grappling. Interposed between the enlarged portion 74 and the recess in the hub 72 is a thrust bearing 77. The shaft 73 is extended rearward through the packing 78 and gland 79, and rigidly mounted thereon and alined with the pulley 67 and driven therefrom by the belt 80 is a pulley 81, for the purpose of rotating the shaft 73 and through the socket 75 and projection 76 the shaft of the fixture employed. Loosely mounted on the shaft 73 are the wheels 82 and 83, the nut 84 and washer 85 serving to limit the end play thereof. To the hub 86 of wheel 81 is attached one end of each of the cords 87, 88. These cords are led by suitable guide pulleys, 89 from the hub 86 along opposite sides of the shell, the other ends being secured to the lever 90, rigidly fastened to one end of the shaft 91 which extends through the packing box 92 and the hub 93 formed on the head 22.

On the opposite side of the centerline of the shell and alined with the hub 93 is a similar hub 94 in the outer end of which is recessed the pivot 95, projecting from the hub of a lever 96 and alining with the shaft 91.

Secured to the outer end of the shaft 91 is a similar lever 97, and connecting the outer ends of the levers 96 and 97, and rigid therewith is the blade 98, forming a rudder, by the action of which, the direction of movement of the apparatus is controlled laterally. The action of the cords 86 and 87 is such, that as the wheel 82 is turned on the shaft 73, one cord is wound about the hub, as the other is unwound, thus shortening the length of one cord directly as the other is lengthened, in the familiar manner. This action results in a rotative movement of the lever 90 on its shaft across the longitudinal center line of the shell, which is transmitted through the shaft 91 and lever 97 to the rudder 98. The rudder 99 is similarly formed, and operated by means of the cords 100, 101, connecting the lever 102 with the hub 103 formed on the wheel 83. The center line of rotation through the hubs 104, 105, being at a right angle with the center line of rotation of the rudder 98, causes the rudder 99 to move in a vertical plane, when actuated by the means above described, thus acting to raise or depress the head end of the device, to change its level through the action of the propeller 45.

The power for operating the motor is received from the storage batteries 36, through the conducting wires 106, 107, the motor being in circuit and controlled by the rheostat 108. Provision is made for reversing the direction of revolution of the motor in the following manner:—

Journalized in the bearings 109, 110 is the shaft 111 to which is rigidly secured one end 10 of the lever 112. The reversing mechanism 113 of the motor 41 is connected to the upper end of lever 112 by means of the link 114 pivoted at 115, 116. Secured to the shaft 111 in a suitable position, is the lever 117, 15 by means of which the shaft 111 is oscillated, and through the intermediate mechanism described, the direction of rotation of the motor 41 is controlled.

The combination of the mechanism above 20 described, all within easy access of the pilot, enables him to advance or recede, change direction of the device, and operate any of the fixtures to be described, for the purpose of grappling either a steel or wooden vessel.

25 The submersion of the device is controlled from the air tanks 37 and water tanks 38 by means of suitable piping and fittings, preferably operated by the assistant. Normally, the total weight of the device with 30 water tanks empty is such that it will float, the inclosed devices and mechanisms being arranged within to trim or preserve levels. The tanks 38 are here arranged in independent units to enable the operator to fill or discharge either tank at will, thus causing a 35 preponderance in weight for the purpose of depressing the bow or stern as may be required, or by filling both tanks to cause the apparatus to submerge. Water is admitted through the inlet 118 and passes 40 through the pipes 119, 120, 121 to the tanks, valves 123 controlling the flow. The air tanks 37 are designed to contain air under pressure and are connected with the water tanks by means of the pipes 124, 125, 126, 45 valves 127 controlling the flow to the tanks 38. Suitably placed and connecting with the air main 124 is the air pump 128 by means of which the pressure in the air tanks 50 may be reestablished when necessary. The tanks 37 are connected by means of the piping 129 and connection 130 for the purpose of maintaining uniform pressure in all the tanks. A check valve 131 between the air 55 pump 128 and the air main 124 insures against the escape of air through the pump when it is inactive. Gage 132 connected to the air main, indicates the pressure in the pipes and tanks, which must be sufficient to 60 clear the tanks, 38, of water, when desired.

Pump 128 is shown as motor driven, the usual connections and switch being omitted in the drawings for convenience.

It is obvious however, that another form

of pump may be used if desired and it is 65 also obvious that instead of expelling the water from the tanks by admitting air under pressure, other expelling means may be employed, for example, an ordinary force pump.

70 A pump 133 similar to pump 128 is employed to exhaust air from vacuum tank 134, which may be securely fastened to one of the water tanks or in any other convenient place. The pipe 135 connects the pump 75 with the tank, a check valve 136, and gage 137 being used for purposes similar to those described in connection with the air pump. From the vacuum tank leads the pipe 138 branching to separate pipes 139, 140 which 80 extend forward to the head lights 141 and are connected therewith. The degree of vacuum in the pipes 139, 140 is independently controlled by means of the valves 142. The purpose of these connections is to control the moisture within the head lights due 85 to temperature changes, which would otherwise cause precipitation or steaming on the lens surfaces from the moisture in the air in the headlights, as the temperature decreases when the apparatus is submerged. By partially exhausting the air from the headlights through the pipes 139, 140 the head lights may be kept free from precipitation.

90 Connecting with the various pipes described are a series of gages 142^a mounted in a suitable position, by means of which, the assistant may have information as to the varying conditions in the general system. 100 Other gages may be employed as required, such as a thermometer, spirit levels or gravity levels, etc. The forward head 21 is provided with two sockets 143 on opposite sides of the axis of the shell. Within these 105 sockets are secured the electric lamps 144, the feed wires of which 145 are connected to the batteries by the usual wiring and switches, omitted in the drawings for convenience. By means of the reflector 146 110 the beam of light is concentrated and passes through the lenses 147, 148 to illuminate the surroundings in front of the apparatus, suitable packing rings 149, 150, 151 being 115 interposed to secure separation of the lenses and a water tight joint when the packing nut 152 is tightened thereon. A port 153 is also provided at a suitable level above the axis of the device to enable the pilot to inspect conditions and observe the action of 120 the fixture used for grappling the vessel. This port is closed by means of the heavy glass, 154, recessed in the head 21 and packaged at 155, 156 against leakage, the frame 157 serving to secure the whole firmly 125 in place.

The several fixtures used in connection with this device are shown in detail in Figs.

4; 4^a, 5, 6, 10, 11. These fixtures are each designed to fit a socket formed in the projection 158, from the forward head 21.

Referring to Figs. 10 and 11, the fixtures shown are used when grappling a sunken vessel in which there are existing ports or other openings through the hull. 159 is a head connected to the body part 160 which has an extension 161 forming a stem to fit the socket in 158. A collar 162 integral therewith, limits the inward movement of the fixtures and serves as a thrust collar against the end of projection 158. The abutment 163 from the collar 161, engages a recess in the end of socket 158 and serves to prevent rotation. A lateral groove 164 cut in the stem 161 is engaged by the cam 165 preventing endwise movement. This cam is secured to the end of the shaft 166 which is journaled in the projection 158 and packed against leakage at 167. A handle 168 is rigidly secured to the inner end of the shaft 166 enabling the operator to rotate the shaft 166 for the purpose of disengaging the cam from the groove and permitting the stem 163 to be withdrawn from the socket. An eye 169 integral with the body 160 is provided, to which may be connected a cable 170 extending to accompanying lighters or other supporting device at the surface. Pivoted at 170 in the head 159 are the arms 171 normally engaging grooves therein. The fixture is bored on its axis to receive a shaft 172 extending to a point near the apex of the head. A portion of this end of the shaft is threaded at 173 and engages with corresponding threads 174 formed in the hubs of the levers. To provide against end movement, this shaft is grooved at 175 near its inner end, and engaged by the set screw 176 in the stem. The shaft 172 is extended beyond the end of the stem 168 and formed at 76 to fit the socket 75 as above described. The operation of this fixture is as follows:—As the device is propelled forward the head 159 passes through the port or other opening in the sunken vessel. The clutch 68 is then operated by the pilot to transmit rotary motion to the shaft 73 and through the socketed joint 75, 76 to the shaft 172. As the shaft is limited in its endwise movement by the set screw 176, the resulting action on the levers 171, rotates them about their axes 55 to the positions shown at *x*. The clutch 68 is released and the cam 165 rotated to disengage the groove 164; the rotation of the motor is reversed, and the apparatus is backed away, leaving the fixture grappling 60 the hull, and connected as above described with the lighter or other supporting means.

This process is repeated until a sufficient number of fixtures are placed, at which time suitable mechanism above is employed to 65 act on the various cables to raise the sunken

vessel. After each fixture is placed in position the apparatus is raised to the surface, another fixture placed in the socket in 158 and the process above described repeated. In order to facilitate the action of raising 70 and lowering of the apparatus, and for the purpose of economizing power in operation, the heads are provided with the eyes 177, preferably integral therewith. To these eyes are connected cables 178, joined to the main 71 cable 179, Fig. 16, which is connected at its upper end with suitable mechanism on the lighter, the lighter being moved to a suitable position above the sunken vessel. The movement of this lighter may 8 be governed by means of telephone connection between the pilot below and the attendant on the lighter. Such an apparatus is indicated at 180 and it is obvious that the conducting wires to the surface may be made 8 integral with the cable 179 or independent, as desired.

Figs. 4, 4^a, 5 show a fixture, for use in grappling a steel vessel which may lack suitable ports or openings at the point where it is desired to attach a cable. A clamp 181 is formed to be set down over the rail 182 of the vessel. An arm of this clamp is formed with the hub 183, to engage the inner side of the vessel and the other arm is provided with an extended hub 184 formed with a tongue 185, to engage a corresponding slot 186 in the holder 187. The hub 184 is recessed in a portion of its length and threaded to receive the sleeve 188, within which is journaled the shaft 189 one end of which is formed at 190 to fit socket 75 and the other end provided with a drill point 191, which journals in the forward part of hub 184, thus furnishing, in connection with the sleeve 188, a stable support for the clamp 181. The hub 183 is bored on the axis of the shaft 189, to a size which will permit the passage of the drill point and shaft. If preferred, the drill portion 191 may be made independently and socketed into the end of shaft 189 in the usual manner employed with drill spindles and interchangeable drills. The holder 187 is formed with a chamber 192 closed by a cap 193, within which is assembled the mechanism required to feed the drill as it bores through the side 194 of the sunken vessel. A preferred form here shown consists of a ratchet 195 rigidly secured to the inner end of the sleeve 188. This ratchet is operated by means of the pawl 196 pivoted in the forked lever 197 which is journaled on the shaft 198 in cap 193. The forked arms of lever 197, engage the eccentric 198, rigidly secured to the shaft 189. The hubs of the ratchet 195, and of the eccentric 198 bear against the walls of the chamber and limit the endwise movement of the drill shaft 189. Pawl 196 is held in contact with the

ratchet 195, by a spring 199, the tension of which is governed by the screw 200. This holder 187 is fitted to the socket 158, held and operated in the same manner as the 5 stem of the grappling fixture first described.

The operation of this fixture is as follows:—The clamp in its extreme forward position in the holder, is lowered over the rail of the sunken vessel, as shown in Fig. 4. 10 As the shaft 189 is rotated from the line shaft 62, by the intermediate mechanism already described, the eccentric in its rotation oscillates the forked lever 197 on its axis 198.

15 The pawl 197 engages the ratchet 195 to rotate the sleeve 188 step by step. The threaded surface of the sleeve engaging the thread in the recess of the hub 184 causes the drill point to advance as it rotates, to 20 and through the side of the sunken vessel, and into the bore of the hub 183. In this position the shaft 189 forms a shackle for the clamp 181 and the fixture may be released from its socket in projection 158, in 25 the manner described in connection with the grappling fixture already described, the eye 201 being provided in the clamp 181 to which may be attached a cable for the purposes already specified.

30 The fixture shown in Fig. 6 may be used for boring through the side of a wooden vessel, and consists of the sleeve 202, in which is journaled the shaft 203 to one end of which is rigidly attached the bur 204. 35 the other end being formed at 205 to fit the socket 75, the stem portion 206 of the sleeve 202 being interchangeable with the other fixtures described. The operation of this fixture is similar to that of the other fixtures, but its purpose differs, in that it is used solely to bore through the sides of the vessel in order that the grappling fixture may be employed. In this fixture, the eye 207 is used only to attach a float line or other 40 45 safeguard against loss of the fixture, by premature release from the socket.

The general operation of my apparatus is as follows:—

50 A lighter or lighters or other tender is used in connection with the apparatus described, a cable being attached to the device as shown, and connected at its other end with suitable winding machinery on the tender. This tender together with the sal- 55 vaging apparatus is guided to an approximate location over the wreck, the purpose being to economize the power within the apparatus for use, so far as possible, only after submerging. The operators having de- 60 scended into the apparatus, and the man-hole being closed, the water tanks are filled, causing the apparatus to submerge as the supporting cable is unwound. As the apparatus sinks, the pilot telephones or signals 65 to the attendants on the tender when a suit-

able depth is reached and from his inspection gives such directions as are necessary to guide the lighter with the suspended apparatus, to a favorable position for operation. Sufficient water is then forced out 70 of the tanks, to cause the apparatus to float at the depth attained.

The attendant is then directed to release tension on the cable sufficiently to insure independent action of the apparatus under 75 its own power, without interference from the tender. The operator then proceeds as described, to grapple the wreck. When this is accomplished he releases the grappling fixture, and backs away leaving the fixture 80 connected by a cable to a suitable buoy or hoisting means. Air pressure is then applied to the water tanks, and as the water is driven out, the apparatus rises to the surface, and is hauled alongside the tender as 85 the cable is wound up. Another grappling fixture is applied to the fixing apparatus, and the process repeated, the compressed air and electric storage being restored as occasion demands, while the device is at the 90 surface.

What I claim is:—

1. A salvaging apparatus, consisting of a submarine vessel provided on its exterior with a fixture adapted to grapple a sunken vessel or other body; a lighting device secured to the submarine, and inclosed in a water tight chamber; means for directing the light through a lens forming a transparent side of the chamber; and means for 95 exhausting the air and vapor from the interior of the chamber, by devices under the control of the operator; and other means for controlling the illumination, and the movements of the submarine, for the purpose of engaging the fixture with a sunken body. 100

2. A salvaging apparatus, consisting of a submarine vessel, provided on its exterior with a socket, adapted to engage the shank 110 of a fixture designed to grapple a sunken body; that fixture; means for securing the fixture in its socket, and for releasing it from the socket; a cable secured to the fixture and supported by suitable buoyant 115 means; a shaft journaled in the wall of the submarine vessel, and provided with an enlarged portion or head, projecting into the socket, and adapted to engage a projection formed on a shaft journaled in the fixture 120 and co-acting with mechanism within a chamber formed in the fixture, for the purpose of securing the fixture to a sunken body; means by which an operator may control the movements of the submarine 125 vessel and the operation of the grappling fixture.

3. A salvaging apparatus, consisting of a submarine vessel, provided on its exterior with a socket, adapted to receive the shank 130

of a fixture, designed to grapple a sunken body; that fixture; means for securing the fixture in the socket, and for releasing it from the socket; a cable secured to the fixture and supported by suitable buoyant means; a shaft journaled in the wall of the submarine, and provided with an enlarged portion or head, projecting into the socket, and adapted to engage a projection, formed on a shaft, journaled in the fixture; a threaded portion of the shaft, engaging mecha-

nism adapted to secure the fixture to a sunken vessel; means for rotating the shaft from devices within the submarine vessel; and controlled by an operator, for the purpose of operating the fixture, and other means for controlling the movements of the submarine vessel. 15

Signed by me at Boston, Massachusetts, this twenty-ninth day of June, 1917.

GEORGE A. LONG.
